UNITED STATES PATENT OFFICE.

LITTLE D. DENNIS, OF PHILADELPHIA, PENNSYLVANIA.

PROPELLER.

1,413,392.

Specification of Letters Patent. Patented Apr. 18, 1922.

Application filed December 23, 1919. Serial No. 346,835.

To all whom it may concern:

Be it known that I, LITTLE D. DENNIS, a citizen of the United States, residing at Philadelphia, in the county of Philadelphia 5 and State of Pennsylvania, have invented new and useful Improvements in Propellers, of which the following is a specification.

It is the primary aim and object of this invention to provide a device of the above mentioned character wherein reciprocating propeller blades are mounted on the stern of a vessel and designed to be alternately arranged in an extended form and in feathered relation during reciprocation for assuring of 15 the propelling of the vessel at a considerably high rate of speed.

As an equally important object this invention contemplates the provision of a device of the above mentioned character wherein 20 improved means is employed for slidably supporting the blades during reciprocation, while acting in conjunction with the supporting means and the blades is the trip means for assuring of the extending of the 25 blades when they reach the inner end of the supporting means and for arranging the blades in feathered relation about the time they reach the end of the outer stroke so that they may be mounted in feathered relation 30 on their inner stroke so as not to retard the speed of the vessel.

More particularly the present invention consists in the provision of a device of the above mentioned character wherein the supporting 35 frame is of novel construction so as to effectively and slidably receive and support the cross bars of the blades during movement as well as a part of the means for imparting reciprocating motion to the 40 blades, the frame being projected exteriorly of the stern of the vessel and also serves incidentally as a means for supporting the rudder.

It is a more specific object of the present 45 invention to provide improved shock absorbing means for absorbing shocks which may be transmitted to the blades upon arranging the same in feathered relation and for also absorbing the shocks at the time the blades 50 are arranged in extended form; to provide improved means for imparting reciprocating motion to the blades and to provide co-operative trip means of an improved construction on the blades and on the supporting 55 frames.

Among the other aims and objects of this invention may be recited the provision of a device of the character described with a view to compactness, and in which the number of parts are few, the construction simple 60 and the cost of production low and the efficiency high.

Other improvements and novel details in the construction and arrangement of the various parts of the apparatus will be 65 brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this connection that minor changes in the construction and arrangement of parts may be made 70 without departing from the principle of operation of the various parts.

The invention is clearly illustrated in the accompanying drawings, in which:—

Figure 1 is a side elevation of the complete 80 device.

Figure 2 is a top plan view thereof.

Figure 3 is a longitudinal sectional detail of the invention.

Figure 4 is a transverse section taken on 85 line 4—4 of Figure 1.

Figure 5 is a perspective detail of one of the propeller blades.

Figure 6 is a longitudinal sectional detail 90 of the packing gland.

Figure 7 is an enlarged longitudinal sectional detail of one of the propellers.

Figure 8 is another detail of the invention.

Similar characters of reference are employed in all of the above described views, 95 to indicate corresponding parts.

Referring now, more particularly, to the accompanying drawings there is provided a main supporting structure or frame indicated generally by the numeral 1 desirably 100 of a rectangular configuration consisting of upper and lower spaced and opposed side bars 2 preferably of a channelled shaped configuration to serve as tracks in a manner to hereinafter become apparent, and these bars are connected to each other by means of transverse braces 3 and diagonally arranged 105 braces 4 so as to increase the rigidity of the bars 2 with respect to each other. The side bars are each projected through the stern 5 110

of the hull 6 of a vessel, bearing plates 7 being desirably employed for receiving and supporting the bars 2. These plates are constructed with central and preferably rectangular bearing openings and are also arranged in pairs so as to project within and beyond the stern of the vessel or in opposite directions with respect to each other so as to form a substantial casing in which is fitted 5 a packing gland or band 8. These glands are disposed about the side bars while suitable adjusting devices such as set screws 9 are mounted through the bearing plates 7 and contact with the glands or bands 8 to 10 maintain the latter in close relation with the side bars, taking up the wear, and providing a water tight joint therebetween. As indicated the side bars of the frame are disposed within the hull of the vessel and are also 15 projected beyond or rearwardly of the stern of the vessel as indicated. Suitable fasteners 10 are extended through the bearings of the plates 7 and anchored to the bars to hold the frame rigid with respect to the hull of the 20 vessel. As shown in the drawings a rudder 11 is operably connected to the outer end of the frame and of course may be turned in any convenient manner for the guiding of the vessel. 25 30 With a view toward providing the improved propelling means opposed slides 12 are mounted in the opposed bars 2 which act as tracks or guides for the slides while the opposed slides are connected at their outer 35 ends by a transverse rod 13 to assure of the opposed slides moving in unison with each other. Swingly connected for vertical movement to the cross rods 13 are relatively movable propeller blades 14, connection with the rods 13 being preferably obtained by means of ears 15 which project from the inner ends of the blades, the side 40 edges of the blades are arranged within the frame, while pivotally connected to the outer 45 edges of the blades by means of pins 16, are links 17, the opposite ends of which are pivoted to the adjacent ends of trip levers 18 in turn pivoted by suitable pintles 19 to the adjacent slide 12 on the free face thereof, 50 as indicated, and the free ends of these trip levers are designed to strike angularly projecting pins or stops 20, projected inwardly from the upper ends of supporting posts 21 and secured to the outer faces of the adjacent 55 bars 2. There is a similar post 23 connected to the outer face of each of the side bars near the hull and of course a pin or stop 24 projects from the upper end of such post as indicated. During reciprocation of the 60 slides 12 the outer ends of the levers will alternately strike the outer pins 20 so as to assure of the swinging of the blades toward each other and into feathered relation and also strike the pins 24 on the inner posts 23 65 about the time the slides reach the end of

their inner stroke to assure of the extending of the blades. Shock absorbing coil springs 25 are connected to the adjacent faces of the blades and in opposed relation with each other so as to contact upon each other upon the feathering of the blades for the absorbing of the shocks likely to be transmitted thereto, as is apparent, also carried with the slides in the rear of the blades and projecting above and below the bars 2 70 75 on the inner faces thereof are blocks 26 formed in their outer faces with recesses 27 for accommodating coiled spring 28 to the outer ends of which springs are connected bumpers 29, the spring serving to yieldably 80 support the bumpers so that the arrangement serves as a means for absorbing the shocks likely to be transmitted to the blades upon the extending of the latter.

As intimated, improved means have been 85 provided for actuating the propellers so that they will reciprocate alternately in opposite directions and in reducing this feature of the invention to practice there is provided a suitable engine indicated generally by the 90 numeral 30, mounted on the floor 31 of the vessel or ship and this flooring desirably aligns with the lower side bars 2 of the frame 1, while the engine includes a pair of cylinders 32 in which are mounted piston 95 heads 33 having connection with piston rods 34. These piston rods are preferably connected to cross head slides 35, in turn slidably mounted in the cross head guide 36 supported by a suitable structure 37 in spaced 100 relation to the floor. The connecting rods 38 have their ends pivotally connected to the cross head slides and also operatively connected to pins 39 carried eccentrically on a rotatably mounted disk 40. In this connection it is to be noted that the pins 39 are arranged in opposed relation with each other, diametrically of the disk so as to assure of the alternate reciprocation of the piston heads. The disk is preferably carried 110 by a shaft 41 which is rotatably mounted in spaced standards 42 on the supporting floor 31, as indicated in the drawings. Other connecting or pitman rods 43 have adjacent ends connected to the opposed pins 115 39, while their outer ends are pivotally mounted as at 44 to a rocking beam 45 carried by a rock shaft 46 which in turn has its respective ends mounted in bearings 47 formed on the upper ends of spaced standards 48 carried by the floor 31. The beam operates in a slot in the floor, while the points of connection 44 are approximately medially of the rocking point of the beam and the outer ends thereof, as indicated in 120 125 the drawings. Elongated links or connecting rods 49 have their respective ends operably connected to the outer ends of the rocking beam 45 and medially of the ends of transverse rods 51 which connect the op- 130

posed slides 12, so that upon actuation of the engine reciprocatory motion will be imparted to the slides.

The mode of operation of the present invention may be reviewed as follows:—

Assuming that the parts have been assembled in the manner described and as indicated in the drawings, upon operation of the engine one of the piston heads 33 will move forwardly to move the adjacent connecting rod 38 correspondingly and owing to the eccentric connection of the said connecting rod with the disk 40 and the eccentric connection of the rod 43 with the disk and its pivotal connection with the lower portion of the rocking beam 45, the latter will be swung rearwardly to shove the elongated link correspondingly to consequently impart a rearward sliding movement to the lower slides 12. As the lower propeller blades are operatively connected to the lower slide the same will be shoved toward the outer portion of the frame 1 against the water, which acts as a resistance for the propelling of the vessel. When the trip levers 18 contact with the stops 20, the former will be swung about their pivots and owing to the link 17 between the levers and the adjacent propeller blades 14, the blades will be quickly folded into feathered relation toward each other forcing the water from between the blades to insure of an effective motion being imparted to the vessel, the springs 25 of course serve to absorb the shocks. Now while the piston head 33 moves in one direction, the other piston head moves in an opposite direction to consequently swing the upper portion of the beam 45 rearwardly owing to the arrangement of the connecting rods 38 and 43 with the disk 40. As the upper portions of the beam swings rearwardly, the adjacent connecting rod or link 49 is moved so as to move the upper slides outwardly, the blades 14 which are connected to the upper slides being arranged in feathered relation until they almost reach the inner end of their stroke and about this time the trip levers 18 strike the pins 24 on the inner posts or standards 23 so as to swing the blades into an extended position so that the said blades

may be moved outwardly, while the lower blades are being drawn inwardly, it being appreciated that the continuous operation of the engine repeats this cycle of operation for the propelling of the ship or vessel. 55 Either one or the other propeller elements may be made to operate as a stopping medium for the vessel in which case the engine must be brought to a state of rest with the trip levers 18 of one of the propellers 60 against the pins of its attendant post when the propeller blades are held in open or extended position, thus interposing a resistance to the progress of the vessel and thereby tending to stop the same. 65

What is claimed is:—

1. A ship propulsion apparatus comprising a propeller consisting of a pair of pivotally connected blades and a slide on which said blades are mounted, blocks mounted on 70 the slides and provided with bumpers for engaging the blades in one position of the latter, pivotally mounted trip levers carried by the slide and disposed in intersecting relation and operatively connected with the 75 blades at intermediate points on the latter, and impact elements disposed for engagement with the trip levers to rock the same and thereby extend the blades in a position to lie substantially in the same plane or to 80 move them to positions in substantial parallelism.

2. A ship propulsion apparatus comprising a propeller consisting of a pair of pivotally connected blades and a slide on which 85 said blades are mounted, blocks mounted on the slides and provided with bumpers for engaging the blades in one position on the latter, pivotally mounted trip levers carried by the slide and disposed in intersecting relation, links connecting the rear end of said trip levers with intermediate points on the blades, and posts provided with stop pins for impact with the trip levers to rock the same and thereby extend the blades to a position 95 to lie substantially in the same plane or to move them to positions in substantial parallelism for the purpose set forth.

In testimony whereof I affix my signature.
LITTLE D. DENNIS.
